UNITED STATES PATENT OFFICE.

LYDIA SMITH PURINTON, OF WESTBOROUGH, MASSACHUSETTS.

CORSET.

SPECIFICATION forming part of Letters Patent No. 320,964, dated June 30, 1885.

Application filed May 13, 1885. (No model.)

To all whom it may concern:

Be it known that I, LYDIA SMITH PURINTON, of Westborough, in the county of Worcester, of the Commonwealth of Massachusetts, have invented a new and useful Improvement 5 in Corsets; and I do hereby declare the same to be described in the following specification and represented in the accompanying drawings, of which—

10 Figure 1 is a front elevation of a corset provided with my invention, it being shown with its fastenings as disengaged. Fig. 2 is a longitudinal section of one of the bone or rib pockets. Fig. 3 is a transverse section, on an 15 enlarged scale, of its two fastening-steels and their pockets in a folded state and containing the fastening-steels and the auxiliary steels. Fig. 4 is a similar section showing each of the 20 pockets in an unfolded state and the steels within it. Fig. 5 is a front view, and Fig. 6 a vertical section on an enlarged scale, of the 25 upper portion of one of the stiffening bone or rib pockets.

The nature of my invention is defined in 30 the claims hereinafter presented, it being to enable each of the ribs, as well as each of the fastening-steels and also each auxiliary steel, hereinafter described, to be readily removed from its pocket to admit of the body of the corset being washed without the steels or 35 ribs being within it.

In Fig. 1 the fastenings of the two fastening-steels A and B of the open front of the corset are shown at *a a a*, &c., and *b b b*, &c., 40 each of those marked *a* being an eye or thin slotted projection, and each of those marked *b* being a button, such steels being common to corsets. Each pocket for reception of one of the stiffening ribs or steels, extending from the 45 waist nearly to the lower edge of the corset, is usually formed by a strip of tape or material, *c*, of suitable width laid upon the corset-body and stitched thereto, the lines *d* of stitches being close to the longitudinal and lower edges of the strip, as shown in Fig. 1. In so making the pocket I also fold down upon itself the strip for about three-quarters of an inch from its upper end, in order to make within the pocket a short auxiliary pocket, closed at top 50 and open at bottom when the strip is sewed to the body, the stitches going through the part so folded down.

In Fig. 5 the line of stitching of the strip *c* to the body *e* is shown at *d d*, and the folded portion of the strip at *c' c'* in Fig. 6. After the 55 stiffening steel or rib may have been placed within its pocket, such rib of steel is to be bent or sprung at its upper end into the auxiliary pocket, which will serve to keep the steel in place in the main pocket and admit of its removal therefrom at any time for any purpose. To effect such removal it will be necessary to bow or slide down the steel and spring it out through the mouth or open upper end of the 60 main pocket. Each of the pockets *g* or *h*, as shown, for holding the steels A B, has a width three times that of the fastening-steel to be inserted in it, and, besides, it has eyes or openings *i* made in it for the extension of the fastenings of the steel through them. Furthermore, there is placed within each of the said 65 pockets an auxiliary steel, *C*, having a width corresponding to that of the fastening-steel. When the pocket is not folded, the fastening- 70 steel and the auxiliary steel are apart from each other a distance equal or about equal to the width of either. 75

With the pocket so made either steel can be readily inserted in or withdrawn from it in 80 case such pocket at the time is in an unfolded state. The fastenings of the fastening-steel can also at the time be inserted in or withdrawn from the lateral openings for their reception. By having the pocket wider, as described, than 85 the fastening-steel, the latter can be moved laterally in the pocket for the purpose of extracting the fastenings from the lateral openings of such pocket, or for introducing such fastenings into such openings. After both 90 steels may have been placed within their pocket the auxiliary steel, with the part of the pocket extending around it, is to be folded laterally twice, so as to cause it to lap on the part of the pocket that may be covering the fastening- 95 steel, all being as shown in Fig. 3. The said fastening-steel will then be securely held in its pocket by the auxiliary steel.

I claim—

1. The fastening-steel pocket having a width 100 three times that of its fastening-steel, and also having eyes or lateral openings for the fastening devices of such steel to extend through, in combination with such fastening-steel, and also

with an auxiliary steel of like width arranged within it, (the said pocket,) and to fold with the pocket against and in rear of the part thereof covering the fastening-steel, all being substantially as set forth.

2. The steel or rib pocket provided at its mouth with a short auxiliary pocket closed at

such mouth, and extending and opening within the main pocket, substantially as set forth.

LYDIA SMITH PURINTON.
